EQUALIZING VALVE MANIFOLD

Robert W. Evans, 11352 SE. Wichita St.,
Portland, Oreg. 97222

Filed Apr. 8, 1968, Ser. No. 11,358

Term of patent 14 years

Int. Cl. D23—01

U.S. Cl. D23—21

FIGURE 1 is a front elevational view of an equalizing valve manifold showing my new design;

FIGURE 2 is a top plan view thereof; and

FIGURE 3 is an elevational view taken from one end thereof.

I claim:

The ornamental design for an equalizing valve manifold, substantially as shown.
